CASE FOR MATCH PACKAGES

Daniel J. McKenzie, Pottsville, Pa.

Application March 5, 1947, Serial No. 732,597

2 Claims. (Cl. 206—33)

1

My invention relates to improvements in cases for match packages, the primary object being to provide a simply constructed, inexpensive pocket case for conventional match packages, adapted for easy quick removal from a pocket and opening in substantially one operation to open the match package so as to expose the matches for removal as desired.

Another object is to provide a case of the character and for the purpose above set forth adapted to hold a match package therein in a manner such that scratch strips on the package are readily accessible either when the case is open or closed.

To the accomplishment of the above, and subordinate objects presently appearing, a preferred embodiment of my invention has been illustrated in the accompanying drawing, set forth in detail in the succeeding description, and defined in the claims appended hereto.

In said drawing—

Figure 1 is a view in front elevation of my improved case in the preferred embodiment thereof;

Figure 2 is a view in edge elevation;

Figure 3 is a view in edge elevation with the body and cover members swung into open position;

Figure 4 is a view in longitudinal section taken on the line 4—4 of Figure 1 and drawn to a larger scale.

Referring to the drawing by numerals, according to my invention, as illustrated, the case compromises, as its basic elements, a pair of substantially rectangular body and cover members 1, 2, respectively, of any suitable light weight, thin gauge, material, the body member being longer than the cover member 2 and said members being pivotally connected together, in a manner presently described, at what constitutes the rear ends thereof for relative swinging into open and closed positions, respectively.

The body member 1 is formed with right-angled side flanges 3 tapering from the rear end of the member, the cover member 2 is formed with similar side flanges 4 adapted to overlap side flanges 3, and a pivot rod 5 extends through the wider ends of the flanges 3, 4, at the rear ends of said members 1, 2, so that said members close to form a case tapering longitudinally from the rear end thereof with the said members 1, 2 spaced apart laterally by said flanges 3, 4 and with the front end of the cover element 2 spaced rearwardly from the front end of the body member 1.

A coil spring 6 surrounds the pivot 5 with its ends bearing against the body and cover mem-

2

bers 1, 2 rearwardly of the pivot rod 5 whereby said spring yieldingly urges said members into closed position.

A suitable protective tube 7 surrounds the coil spring 6 between the flanges 3 of the body member 1 and acts as a filler for closing the space between the rear ends of the body and cover members 1, 2.

A pair of edge finger grip rolls 8 are formed on the rear ends of the body member 1 and cover member 2 in the rear of the pivot rod 5 for grasping and pressing together to swing said members 1, 2 open in opposition to the coil spring 6.

A lip 9 is bent forwardly on the front end of the body 1 to form a front end channel 10 extending across said member.

A similar lip 11 is bent rearwardly on the front end of the cover member 2 to form an internal front end channel 12 extending across said cover member.

A rectangular opening 13 is provided in the cover member 2 of sufficient size to expose to view the major portion of the closure flap 14 of a match package 15 having an edge scratch strip 16 on the free end of said flap.

The described case is designed to contain the match package 15 between the body and the cover members 1, 2 and which is secured therein by inserting the usual match fastening fold 17 into channel 10 of the body member 1 and the free end of the closure flap 14 into channel 12 of the cover member 2, as shown in Figure 4. The match package 15 being thus inserted in the case, the usual scratch strip 18 on the base of the match package 15 is exposed for use in the space between the front end of the cover member 2 and the front end of the body member 1, the scratch strip 16 on the closure flap 14 being exposed for use through the opening 13, also any advertising matter on said flap 14. The case being carried in the pocket may be grasped by the finger grip rolls 8 pulled from the pocket and simultaneously opened by pressing on said rolls 8 to swing the body and cover members 1, 2 apart and thereby open the match package 15. As shown in Figure 3, the finger grip rolls 8 are adapted to abut and limit the extent to which the body member 1 and cover member 2 may be opened.

Pressure being relieved on the finger grip rolls 8, the body member 1 and cover member 2 will swing closed under the influence of the coil spring 6.

The foregoing will, it is believed, suffice to impart a clear understanding of my invention, without further explanation.

Manifestly, the invention, as described, is sus-

ceptible of modification, without departing from the inventive concept, and right is herein reserved to such modifications as fall within the scope of the appended claims.

What I claim is:

1. A case for a match package of the type having a match retaining fold, a closure flap and a base scratch strip, said case comprising a rectangular body member having sides, a rectangular cover member, said members being adapted to accommodate said package therebetween, means pivotally connecting said members at rear ends thereof for relative swinging into open and closed positions, respectively, and to form the case when in closed position, said body member having a front end channel therein adapted to seat therein the match retaining fold of the match package, and said cover member having a front end channel therein adapted to seat therein the free end of the closure flap of said package, whereby said package is adapted to be opened by swinging of said members into open position, said cover member being shorter than said body member with the front end thereof spaced from the front end of said body member rearwardly of the front end of the body member when said members are closed so that said scratch strip is exposed between said ends, a helical spring between the rear ends of said members extending from side to side of the body member and attached to said members for swinging the same into closed position, and a protective tube surrounding said spring and closing the case at the rear ends of said members.

2. A case for a match package, said case comprising a rectangular body member having sides, a rectangular cover member, said members being adapted to accommodate said package therebetween, means pivotally connecting said members at rear ends thereof for relative swinging into open and closed positions respectively, and to form the case when in closed position, a helical spring extending between the rear ends of said members from side to side of the body member and attached to said members for swinging the same into closed position, and a protective tube surrounding said spring and closing said case at the rear ends of said members.

DANIEL J. MCKENZIE.
